UNITED STATES PATENT OFFICE.

HORACE THURSTON, OF PROVIDENCE, RHODE ISLAND, ASSIGNOR TO JOHN C. SCHOTT AND CHAS. H. SCHOTT, BOTH OF SAME PLACE.

SHOE-LACE-TIPPING MACHINE.

SPECIFICATION forming part of Letters Patent No. 373,865, dated November 29, 1887.

Application filed September 2, 1887. Serial No. 248,567. (No model.)

To all whom it may concern:

Be it known that I, HORACE THURSTON, residing in Providence, Providence county, Rhode Island, have invented an Improved 5 Tipping-Machine, of which the following is a specification.

The object of my invention is to produce a machine for placing tips upon strings, lace-cords, &c., such as are used for shoes, corsets, 10 and the like, and also for pointing said tips.

The invention consists in the combination, with a grooved base, of two sliding plates carried in a suitable guide on the machine and placed face to face, each plate preferably having a specially hollowed end. The hollowed 15 ends of the plates are adapted to enter the recess in the base and roll the tip-blank into a cylinder and to fasten it upon the string or cord.

20 The invention also consists in the combination, with said plates, of a lever carried by the machine, which lever passes through slots in the plates. Said slots are so arranged with relation to the lever that the plates will be 25 moved together by the said lever, but at certain times at different speeds, and then into the said recess together to roll the blank.

The invention also consists in the combination, with said base, of a nick or recess on the 30 edge of the tip-forming groove and of a nick on the lower edge of one of the sliding plates, which nicks are adapted to register when said plate is lowered into the recess. By placing the end of a completed tip in the nick in the 35 base and lowering the said plate the end of the tip will be pointed by said nicks and any projecting pieces cut off by the edge of the plate.

The invention also consists in details of construction and combinations of parts, as will be 40 more fully hereinafter set forth.

Reference is to be had to the accompanying drawings, forming part of this specification, in which—

Figure 1 is a side view of a tipping-machine 45 constructed according to my invention. Fig. 2 is a face view of the same. Fig. 3 is a vertical cross-section through the sliding plates, their guide, and part of the base, the lever being broken off, showing said plates in the raised 50 position, with the blank in the position it as-

sumes before being rolled. Fig. 4 is a similar view to Fig. 3, showing the sliding plates in the positions they assume before they enter the recess in the bed, the tip having been partly rolled. Fig. 5 is a view similar to Fig. 55 3, showing the sliding plates in the lowermost position within the recess in the bed and the completed tip in position upon the string. Fig. 6 is a vertical cross-section through the lower part of the sliding plates and part of the 60 guide and base, showing the end of a tip in position to be pointed. Fig. 7 is a face view of one of the blanks. Fig. 8 is a view showing the end of a string having a completed tip applied. Fig. 9 is an enlarged section of the 65 parts that roll the blank.

A in the drawings represents the base of my improved tipping-machine. The base A is provided on its upper face with a transverse groove or recess, *a*, preferably of the form 70 shown.

B D are two sliding plates adapted to enter the recess *a*, and arranged face to face, as shown. The plates B D are supported and slide in a grooved post, E, which projects from 75 the base A. The plates B and D are by preference provided with guide-slots for receiving a pin or screw, *b*, which passes through said slots into the post E to hold the plates in position; but other means may be used for this 80 purpose, if desired. The lower edge of each of the plates B and D is preferably hollowed out in the form approximating a quarter-circle, as shown at *d e*, so that when the lower edges of said plates are brought together, as in Fig. 5, 85 the two hollows will together form a semicircle. The upper parts of the plates B and D are provided with slots *f g*, respectively, which slots are adapted to register when the plates are in the position shown in Figs. 1 and 5, and 90 to be more or less out of line when in the positions shown in Figs. 3 and 4, for the purposes hereinafter stated.

F is a lever which is pivoted to a lug, *h*, on the post E back of the sliding plates B and D. 95 The lever F projects through the slots *f g* in the plates B and D, as shown. By operating said lever the plates B and D will be reciprocated lengthwise, as hereinafter stated.

i is a nick or recess in the base A on the edge 100

of the groove or recess *a*, as shown. *j* is a corresponding nick or recess on the lower edge of the sliding plate *B*, and it is arranged to register with the nick *i* when the grooved lower edge of the plate *B* enters the recess *a*.

This tipping-machine operates as follows: The lever *F* is first moved upward. This carries the plates *B D* substantially into the position shown in Fig. 3—that is, with their lower edges out of line and out of the groove *a*. A tip-blank, *G*, and a string or cord, *m*, are now passed into the recess *a*, the lower slightly-bent part of the tip-blank being preferably turned toward the front of the machine, as shown in Fig. 3. The upper edge of said blank *G* now rests against the sloping lower end of the plate *B*. The lever *F* is now brought down to roll the tip and bears upon the lower ends of the slots *f g*, so as to move the two plates *B D* downward together at this time at nearly equal speed. During this descent of said plates the upper end of the blank *G* is confined between the plates *B D*, so that it cannot drop backward or forward. This is shown in full lines in Fig. 3. As the lever *F* continues to descend, it now moves the plate *B* a little faster than the plate *D*, this being caused by the part of the lever *F* over the edge of the slot *f* moving faster than the inner part. This gradually brings the edges *d e* of the said plates into the position shown in Fig. 4. While the plates have been descending, as described, they have rolled the lower part of the blank partly around the string in the groove *a*, as shown in Fig. 4. A further downward movement of the lever causes the two slots *f g* to register, as in Fig. 5. This brings the ends of the plates *B D* together, the grooves *d e* forming a semicircle, as in Figs. 1 and 5. A further depression of the lever *F* now carries the two plates *B D* together farther into the recess *a*, completely rolling the blank around the string. During all the time that the plates *B* and *D* are descending the blank *G* is being gradually rolled. The lever *F* is now raised and the tip on the string removed from the recess *a*. To form a point on the tip, the end of the rolled tip is placed in the nick *i*. (See Fig. 6.) The lever *F* is now depressed to bring the plate *B*, with its nick *j*, down upon the tip. This jams the end of the tip between the nicks *i* and *j*, forming a point, and any projecting end of tip and string will be cut off

by the edge of the plate *B*. The plate *D* is not essential to this operation and could be dispensed with, if desired, the plate *B* alone performing the work of pointing the tip, as it is not necessary to push the end of the tip far enough under the plates *B D* to be operated upon by the plate *D*. The plates *B* and *D* move when the lever *F* is operated, whether the plate *B* alone or both the plates are performing a function.

Although I have shown in the drawings the ends *d e* of the plates *B D* grooved, these ends could be flat or of other suitable shape for rolling the tip in the groove *a*.

Having now described my invention, what I claim is—

1. In a tipping-machine, the base *A*, having the groove *a*, combined with the sliding plates *B D*, both adapted to enter the groove *a* to roll a tip-blank, and with means for operating the plates *B D*, substantially as described.

2. In a tipping-machine, the grooved base *A*, combined with the sliding plates *B D*, having grooved ends *d e*, which form a semicircle when brought together, and with the lever *F*, substantially as described.

3. The grooved base *A* and sliding plates *B D*, combined with the lever *F*, adapted to move the plates *B D* at even and different speeds, substantially as described.

4. The grooved base *A*, combined with the grooved sliding plates *B D*, having slots *f g*, and with the lever *F*, adapted to pass through said slots, said slots being arranged to register when the lever is depressed, but to be out of line when the lever is raised, substantially as described.

5. The base *A*, having groove *a* and nick *i*, combined with the plate *B*, having nick *j*, and lever *F*, all arranged so that the nicks *i* and *j* will register when the plate *B* enters the recess *a* for the purpose of pointing a tip and cutting the same, substantially as described.

6. The combination of the grooved base *A*, having nick *i*, with the reciprocating plates *B D*, having grooved ends *d e* and nick *j*, all arranged for turning a tip-blank and for pointing and cutting it off, substantially as specified.

HORACE THURSTON.
